Thos. J. Sprague

UNITED STATES PATENT OFFICE.

ISAAC DE GRAFF, OF DETROIT, MICHIGAN.

ENGINE.

SPECIFICATION forming part of Letters Patent No. 297,506, dated April 22, 1884.

Application filed October 1, 1883. (No model.)

To all whom it may concern:

Be it known that I, ISAAC DE GRAFF, of Detroit, in the county of Wayne and State of Michigan, have invented new and useful Improvements in Engines; and I do hereby declare that the following is a full, clear, and exact description thereof, reference being had to the accompanying drawings, which form a part of this specification.

10 This invention relates to certain new and useful improvements in the construction of engines.

The invention consists in the peculiar construction of the parts, and the means employed 15 for adjustably securing the engine upon its frame, all as more fully hereinafter set forth.

It has been found difficult in all end-support horizontal engines to so secure them upon their frame that they will not pound or vibrate

20 under various conditions of work; and the object of my invention is to provide a means for securing it upon its frame in such a manner as to avoid all lateral and vertical play, while the cylinder is free to expand and contract horizontally.

Figure 1 is a top plan with the cylinder partly broken away. Fig. 2 is an end elevation with one-half of cylinder in cross-section.

In the accompanying drawings, which form 30 a part of this specification, A represents the base and frame of a horizontal engine, and B the cylinder, the front end of which is rigidly bolted to the frame, as in the ordinary manner. At the rear end of the frame, and forming an integral part thereof, I form the post 35 C, in the top face of which is formed a dovetailed seat with parallel sides.

D is a foot, which is preferably cast as an integral part of the cylinder B, and such foot 40 is provided with inclined flanges a, with parallel faces, and corresponding in form to the dovetail recess or seat of the post C, the lines or faces of these parts being parallel with the axis of the engine. This foot D

45 rests within the dovetailed recesses in the post C, and between their edges I introduce

wedges E, the inner faces of which are parallel with the faces of the flanges a, while their outer faces are inclined to form the wedges. These wedges are driven tightly to place, where 50 they are secured to the frame or post C by means of a bolt or bolts, b, which pass through the heads of the wedges and are tapped into the frame.

By this construction and arrangement of 55 parts it can readily be seen that all lateral movement of the cylinder, and all vertical movement, either up or down, is positively avoided, while the cylinder is free to expand longitudinally, it having the parallel faces of 60 the wedges to travel between. If, after continued use, the wedges should become a little loose, so as to cause the cylinder to vibrate, the wedges may be readjusted by turning up the bolts b.

It can readily be seen that instead of providing the wedges with heads, as shown, plates to cover their outer ends may be secured to the frame and accomplish the same end.

It will be observed that my post C is formed 70 integral with the frame A, and that the foot D is also integral with the cylinder B, and this foot rests within the recess in the post C, thus forming, as it were, a solid structure with no loose parts to become displaced by the working of the engine, as would be the case where the tenons are made separately and attached to the cylinder and work in recesses in castings attached to the sides of a boiler, as has heretofore been proposed.

80 What I claim as my invention is—

The connection between an engine and its frame, as herein described, the foot D, engaging by a tenon in an undercut mortise in the post C, and provided with wedges and devices 85 for holding the same, substantially as and for the purposes set forth.

ISAAC DE GRAFF.
